RALPH BERTSCHE, JR., OF ANDERSON, INDIANA, ASSIGNOR TO DELCO-REMY CORPORATION, OF DAYTON, OHIO, A CORPORATION OF DELAWARE

ENGINE STARTER

Application filed November 15, 1928. Serial No. 319,696.

This invention relates to engine starters which comprise a motor driving a pinion which is manually movable endwise into mesh with a gear connected with the engine to be started.

One object of the present invention is to minimize breakage of gear teeth resulting from attempting to mesh gears while the starting motor is operating. This aim is accomplished by an improved manually operable means for compelling the pinion to turn relative to the engine gear while being manually pressed against the engine gear in order to compel the pinion to mesh with the engine gear to a substantial degree before the starting motor is caused to operate. More particularly, the present invention provides for rotating the pinion normally in a certain direction in case of gear tooth abutment, and also in the opposite direction in case rotation in the normal direction is abnormally resisted.

The present invention is illustrated and described in connection with an engine starter which comprises a shaft operated by an electric motor and means for connecting the shaft with a gear of an engine to be started, said means including a pinion mounted on the shaft for longitudinal movement thereof into mesh with the engine gear and rotary movement therewith for driving the engine gear, said means including also provisions whereby the pinion will be automatically demeshed from the engine gear when the engine starts. In the preferred form of engine starting apparatus of this type the shaft is provided with helical splines with which the pinion is connected and along which the pinion is slidable.

This starter includes a mechanism which can be operated manually or by foot pressure to move the pinion into mesh with the engine gear and afterward to close a switch which will cause the motor to turn the shaft, said mechanism including provisions where-

by the pinion will be rotated in the two directions mentioned to compel the pinion to move into meshing registration with the engine gear, in case the teeth of the pinion collide with the engine gear teeth. The mechanism is so arranged that the pinion will be automatically demeshed regardless of whether the operator fails to release the manually actuatable member which controls the gear shifting mechanism.

One form of engine starter to which the present invention may be applied is disclosed in the copending application of John B. Dyer, Serial No. 245,300, filed January 9, 1928.

Further objects and advantages of the present invention will be apparent from the following description reference being had to the accompanying drawings, wherein a preferred form of embodiment of the present invention is clearly shown.

In the drawings:

Fig. 1 is a fragmentary, side view, partly in longitudinal section, of a starting apparatus embodying the present invention, the sectional view being on the line 1—1—1 of Fig. 2.

Fig. 2 is a fragmentary, sectional view on the line 2—2 of Fig. 1.

Fig. 3 is a fragmentary view looking in the direction of arrow 3 of Fig. 2.

Fig. 4 is a fragmentary view looking in the direction of arrow 4 of Fig. 3.

Fig. 5 is a view similar to Fig. 1 showing the condition of the engine starting apparatus at the instant of bringing the pinion into meshing relation with the engine gear, the sectional view of Fig. 5 being taken on the line 5—5—5 of Fig. 6.

Fig. 6 is a fragmentary, sectional view on the line 6—6 of Fig. 5.

Fig. 7 is a view looking in the direction of the arrow 7 of Fig. 6.

Fig. 8 is a view similar to Fig. 5 showing

the condition of the apparatus at the instant of closing the motor switch.

Fig. 9 is a view similar to Fig. 8 showing the condition of the apparatus after the engine becomes self-operative and before the actuator has been released by the operator.

Fig. 10 is a fragmentary, sectional view on the line 10—10 of Fig. 9.

Fig. 11 is a view looking in the direction of the arrow 11 of Fig. 10.

Fig. 12 is a fragmentary view looking in the direction of the arrow 12 of Fig. 10.

Fig. 13 is a perspective view of the sleeve element of the apparatus.

Fig. 14 is a plan view of a sheet metal blank used to form a part of the element shown in Fig. 13. Fig. 14 shows also diagrammatically the relative positions of certain parts with which the sleeve is operatively associated, these positions being taken relatively during the operation of the starter.

Figs. 15 to 19 are sectional views respectively on similarly marked section lines of Fig. 14.

Fig. 20 is a view similar to Fig. 9 and shows the positions of certain parts after the starter has been operated to compel rotation of the pinion in case rotation of the pinion by manual effect has been abnormally resisted.

Referring to the drawings, the field frame 20 of the starting motor is secured in any suitable way to a bracket and gear housing frame 21 which is adapted to be secured in the usual manner to that part of the engine frame which encloses the engine flywheel which is provided with a gear 22. The starting motor includes an armature shaft 23 journaled in a bearing 24 provided by the frame 21 and at the opposite end, in a similar bearing, supported by the field frame in the usual manner. The shaft 23 is provided with helical splines 25 which, between shoulder portions 25a and 25b, are less in external diameter than other portions of these splines for a purpose to be described. A pinion 26 is provided internally with spiral splines adapting the pinion to slide endwise along the shaft splines 25 into mesh with the engine gear 22, and adapting the pinion to be driven by the shaft 23 for the purpose of cranking the engine. When the pinion 26 is in normal position out of mesh with the engine gear, its internal splines are supported upon that portion of the splines 25 between the shoulders 25a and 25b. Since the pinion must be elevated in moving from the position shown in Fig. 1 to that shown in Fig. 5 in passing over the shoulder portions 25b, it is evident that the pinion will be yieldingly retained in normal position thus overcoming a tendency to drift into engagement with the engine gear due to vibration of the engine or vehicle propelled by it. As the pinion is moved into mesh with the engine

gear by a mechanism to be described, an internal annular shoulder 27 provided by the pinion will engage a resilient wire split ring 28 and will cause it to be contracted within a groove 29 which the shaft 23 provides for receiving the ring. The internal diameter of the shoulder 27 is such that the shoulder will be permitted to move toward the right past the ring 28 while the ring is being squeezed into the groove. After the shoulder 27 has moved past the ring 28, the ring will expand within an internal annular groove 30 in the pinion and will therefore yieldingly retain the pinion in gear meshing position. While the pinion is being operated by the motor to crank the engine, the conical surface 31 provided by it, will abut the ring 28 which delivers the end thrust from the pinion to the shaft 23. End thrust is delivered from the shaft 23 to the frame 21 through a washer 32 received by a groove 32a in the shaft 23 and bearing against a machined surface provided by the frame 21.

The manually operable mechanism for moving the pinion into mesh with the engine gear and for causing the motor thereafter to operate comprises a pedal rod 40 which slides through a floorboard 41 of an automobile and is connected at 42 with a lever 43 pivoted upon a screw 44 attached to the frame 21. The lever 43 is arranged to contact with a switch actuating plunger 45 supported by a case 46 which is attached by screws 47 to the field frame 20 and which encloses the switch contacts. When the switch actuator 45 is in the position shown in Fig. 1, the switch is open and when in the positions shown in Figs. 8 and 9 the switch is closed. A spring 48 moves the actuator 45 from the switch closed to switch open position. The lever 43 carries at its lower end a pin or stud 50 adapted to be received by the oblique slot 51 provided in the sleeve 52 which is formed by bending the sheet metal blank 53 shown in Fig. 14 into cylindrical form. A tubular rivet 54, which is slideable along the shaft 23, cooperates with apertured discs 55 as shown in Fig. 1 in order to hold the sleeve 52 in concentric spaced relation to the tubular rivet 54. The blank 53 used to form the sleeve 52 is provided with notches 57 and 58, which after the sleeve 52 has been formed into a cylinder and assembled with the parts 54, 55 and 56, receive respectively lugs 59 and 60 which are struck from the discs 55 respectively as shown in Figs. 4 and 13 respectively. By the conventional staking operations, the discs 55 are connected with the rivet 54.

Rotation in either direction is imparted from the sleeve 52 to the pinion 26 by axially engageable clutches, the driving clutch 56 being provided by a sleeve having clutch teeth 62 adapted to engage clutch teeth 63 provided by shaping the adjacent ends of

the teeth of the pinion 26. The sleeve 52 and its clutch 56 are connected for limited linear and rotary movement by providing the clutch 56 with inwardly extending tangs 156 received by notches 157 provided by the sleeve 52 and including oblique portions. Relative linear motion between the sleeve 52 and its clutch 56 is resisted by a spring 158 surrounding the sleeve hub 54 and bearing at one end against the tangs 156 and at its other end against a spacer sleeve 159 abutting the left end disc 55.

Obviously the force applied by the pin 50 to the sleeve 52 tends not only to move the sleeve endwise but also to rotate it. Since it is desirable to begin the operation of gear meshing by simply pushing the sleeve 52 endwise in order to move the pinion 26 into engagement with the engine gear 22 and to reserve the operation of rotating the sleeve until the time it is needed in order to bring the pinion into meshing registration with the engine gear, the apparatus provides for resisting rotation of the sleeve so that the relation of the slot 51 and the pin 50 will be maintained at least during that portion of the movement of the sleeve which is required to push the pinion into contact with the engine gear. The means which resists rotation of the sleeve under these conditions is provided by a plunger 70 which is slidably supported radially of the shaft 23 by a recess 71 provided by the frame 21, and which is pressed by a spring 72 against a projecting portion 73 of the sleeve which defines a longitudinally extending ridge 74 relatively gradual. The projection 73 is formed by partially shearing away the metal of the blank 53 along the line *a*—*b* and *c*—*d* shown in Fig. 14 and in shaping this portion as shown in perspective in Fig. 13. The projection 73 therefore provides a surface 75 against which the plunger 70 normally rests, the ridge 74 which is at a greater distance radially from the center of the shaft 23 than the surface 75, and a surface 76 which extends from the ridge 74 to the main cylindrical portion of the sleeve 52. Movement of the pin 50 toward the right in the drawings for the purpose of pushing the pinion 26 into engagement with the engine gear 22, will tend to rotate the sleeve 52 in a clockwise direction as viewed in Fig. 2. It is obvious that due to the engagement of the plunger 70 with the ridge 74 rotation of the sleeve 52 will be yieldingly resisted.

The blank 53 is cut out along the curved lines *d*—*g* and *g*—*h*—*d* to form an opening and the metal is sheared along the lines *g*—*f* and *f*—*e* in order to permit the formation of a lug 77 which may be described as starting from the ridge 74 and so shaped as to provide a portion 78 which as shown in Fig. 2, extends away from the sleeve 52 and which as shown in Fig. 4, slopes from a portion 78a most re-

note from the sleeve 52 over to the portion 78b which merges with the sleeve. The edge portion 79 of the lug 77 provides a stop for engagement with the plunger 70 for a purpose to be described. From the portion 78b to the free end of the lug 77 the lug diminishes in width as shown particularly in Figs. 11 and 3 in order to provide clearance for the motion of the lug 77 relative to the plunger 70 without the lug touching the plunger. 75

In order that there may be a tendency for the sleeve to rotate with the shaft, the sleeve is provided with a hole 80 (see Fig. 14) for receiving the shank 81 of a plunger 82 extending through a hole 83 in the tube 54 and pressed by a spring 84 against the shaft 23 as shown in Fig. 2. By connecting the shaft and sleeve with a friction coupling the shaft causes the sleeve to be automatically retracted from the pinion in a manner and for a purpose which will be apparent hereafter. 80 85

The pedal 40 is yieldingly retained in normal position as shown in Fig. 1 by a spring 90 retained by a recess 91 in the frame 21 and pressing the head 92 of a plunger 93 surrounded by the spring into engagement with the lever 43 tending to rotate the lever clockwise. 90

The operation of the invention is as follows: 95

To start the engine, the operator will press the pedal 40 causing the lever 43 to move clockwise and the sleeve 52 to move into engagement with the pinion 26 and the pinion to move into engagement with the gear 22 as shown in Fig. 5. During this motion of the sleeve endwise the plunger 70 remains in engagement with the surface 75 and the ridge 74 and thereby yieldingly resists rotation of the sleeve 52 in a clockwise direction as viewed in Fig. 2, although, during the endwise movement of the sleeve 52, the pin 50 coacts with the sleeve in such manner as to tend to rotate the sleeve in this direction. By the time the pinion has been pushed by the sleeve against the gear 22 the relative motion between the plunger 70 and sleeve will be such that the plunger will occupy the position indicated by the dash and dot line circle 70a in Fig. 3. 100 105 110 115 120 125 130 Assuming that the ends of the pinion teeth abut the ends of the gear teeth 22 before meshing, endwise motion of the sleeve 52 will be arrested. If the operator continues to press the pedal 40, the sleeve will be rotated due to the cooperation of the pin 50 and the walls defining the oblique slot 51. By reason of the clutch teeth 62 and 63, rotation is transmitted from the sleeve 52 to the pinion 26. The lug 77 will therefore rotate relative to the plunger 70 in order to bring the plunger 70 in new relation to the sleeve. At the instant the pinion has been located in meshing registration with the gear, the plunger will be located relative to the lug 77 as shown in Figs. 5, 6 and 7. It will be seen that the plunger is

located upon substantially the highest part of the surface 78 or that part most remote from the shaft. Relative to the sleeve 52, the plunger 70 has moved from the position 70a in 5 the direction of the arrow 95 into the position represented by the dash and dot line circle 70b.

As the operator continues to press the pedal 40, the sleeve and pinion will move from 10 the position shown in Fig. 5 to that shown in Fig. 8, and during this movement, the lug 77 will slide from contact with the plunger 70. The relative motion of the plunger and sleeve is indicated by the arrow 96 in Fig. 3, 15 and when the plunger is located relative to the sleeve as shown in Fig. 8, the plunger will be located as represented by the dash and dot line circle 70c in Fig. 3. During the movement of the sleeve from the position shown 20 in Fig. 5 to that shown in Fig. 8, the inclined surface between the parts 78a and 78b of the lug 77 will be engaged by the plunger. Therefore as the sleeve moves toward the right in the drawings; the plunger will be permitted 25 to approach the shaft. When the surface 78 is well lubricated the plunger will actually assist to move the pinion into engagement with the gear.

The sleeve is now free of the pinion and is 30 prepared to be automatically retracted from the pinion so that when the pinion is thrown out of mesh with the engine gear it will not be hindered by the sleeve.

By the time the lever 43 has been moved 35 sufficiently to locate the sleeve and pinion as shown in Fig. 8, the motor switch will be closed to cause the shaft 23 to rotate in a clockwise direction when viewed in the direction of the arrow 8a in Fig. 8. Due to the 40 helical splined connection between the pinion 26 and the shaft 23, the motor will automatically move the pinion the position shown in full lines in Fig. 8 to the dot and dash line position 26a, thereby moving the pinion 45 into engagement with the stop ring 28 and connecting the pinion for rotation with the shaft. The pin 50 of the lever 43 being stationary during the engine cranking operation, the sleeve 52 will be automatically 50 moved from the position shown in Fig. 8 to that shown in Fig. 9 due to the cooperation between the pin 50 and the sleeve walls defining the spiral slot 51. The sleeve 52 tends 55 to follow the shaft since it is frictionally connected with it by the spring pressed plunger 82. When the sleeve is in the position shown in Fig. 9 and before the pedal is released, the relation of the sleeve and plunger is as shown 60 in Figs. 9, 10, 11 and 12. During the movement of the sleeve 52 from the position shown in Fig. 8 to that shown in Fig. 9, the relative motion between the plunger and sleeve is indicated by the arrow 97 in Fig. 3. The location 65 of the plunger 70 relative to the sleeve as

shown in Figs. 9 to 12 inclusive is represented by the end portion 70d of the plunger indicated by dot and dash lines in Fig. 3. Since the path of relative movement of the plunger as indicated by the arrow 97 is necessarily 70 parallel to the oblique slot 51 in the sleeve 52, it is apparent that the lug 77 must be tapered as shown in order to avoid contact between the plunger 70 and lug 77 while the lug moves relative to the plunger. 75

When the engine becomes self-operative, the pinion will be automatically demeshed from the engine gear due to the fact that there is a reversal of torque transmission between the gear 22 and pinion 26 since the gear is driving the pinion faster than it can be driven by the motor. The pinion will therefore be automatically moved into the position shown in Fig. 9 after the engine becomes self-operative. However, before this occurs the sleeve will have been moved into the position shown in Fig. 9 so that the pinion may be automatically demeshed without colliding with the sleeve. When the operator releases the pedal 40, the spring 90 will be 90 released to move the lever 43 clockwise and to restore the normal relation between the pin 50 and sleeve 52 as shown in Fig. 1. While the pin 50 moves from the position shown in Fig. 9 to that position shown in 95 Fig. 1, the sleeve 52, being resiliently urged against a stop member 100, will be rotated from the position shown in Fig. 9 to that shown in Fig. 1 or in a clockwise direction 100 as viewed in Fig. 2. During this motion of the sleeve relative to the plunger 70 the inclined surface 76 will first engage the plunger and then the ridge 74; and, when the rotation of the sleeve ceases, the plunger 70 will be 105 located in normal position against the surface 75 and the ridge 74. The relative motion between the plunger 70 and sleeve 52, as the sleeve 52 returns to normal is represented by the arrow 98 in Fig. 3. Relative to the sleeve 52, the plunger moves from the position represented at 70d in Fig. 3 to the normal position 70. All of the parts of the apparatus 110 have been restored to normal position after the pedal has been released.

Provided the pin 50 and sleeve 52 are in 115 normal relation before the pedal 40 is pressed, the motor switch cannot be closed until after the pinion 26 has been substantially meshed with the engine gear 22. This feature is due to the fact that the lever 43 is not permitted 120 to engage the motor switch actuator 45 until after the sleeve 52 has pushed the pinion 26 against the gear 22, has rotated the pinion into meshing registration with the gear and has pushed the pinion into substantial 125 mesh with the gear as shown in Fig. 8. This feature insures a substantial engagement of the gear before the motor switch is closed and thereby avoids the breakage of gear teeth which would be likely to occur if the area 130

of tooth contact pressure were but very slight at the time the full power of the motor comes on. Provided that the pin 50 and sleeve 52 are at normal relation when the starting operation is initiated, the plunger 70 will cooperate with the sleeve in such manner as to cause the sleeve to perform the functions described. One of the features of the type of starter to which the present invention may be applied is the means for compelling the operator to restore to normal the relation between the pin and the sleeve before the operation of starting can be repeated. It will be noted that if the operator releases the pedal at least sufficiently to effect the rotation of the lug 77 from the position shown in full lines to the position 77a in dot and dash lines in Fig. 10, depressing the pedal again in order to move the sleeve endwise toward the pinion will cause the lug 77 to engage the plunger 70, thereby preventing further movement of the sleeve toward the pinion. Therefore if the lever has been released to this extent the operator cannot repeat the starting operation unless he first releases the pedal to permit the normal relation of the sleeve and plunger and pin and sleeve to be restored or in other words, to remove the obstruction provided by the side edge 79 of the lug 77. If, however, the pedal 40 is released only slightly, for example, sufficiently to open the motor switch but not enough to locate the lug 77 in longitudinal alignment with the end of the plunger 70, depressing the pedal again will not move the sleeve sufficiently to move the pinion into contact with the engine gear, although, the closing of the motor switch will be permitted. The sum of the clearances between the sleeve and the pinion and the pinion and gear shown in Fig. 9 is such that counterclockwise rotation of the lever 43 is stopped by the motor switch before the pinion can be moved into contact with the gear. Therefore, under no condition can a trick manipulation of the pedal be performed in order to bring about the closing of the motor switch while the ends of the pinion teeth are only pressed into engagement with the ends of the gear teeth. The lug 77 is therefore effective in preventing the re-engagement of the pinion with the engine gear unless the sleeve 52 has first been returned to a position permitting the re-engagement of the plunger 70 with the portions 75 and 74 of the sleeve extension 73, or unless the pin 50 and oblique slot 51 have been restored to the normal relation which is necessary before the sleeve can be caused to perform its usual functions, namely, moving the pinion endwise into engagement with the engine gear, rotating the pinion into gear meshing registration with the engine gear and then pushing the pinion part way into mesh with the engine gear before closing the motor switch.

In case that rotation of the pinion while being pressed against the engine gear is not abnormally resisted, the operation of the starter will be as described heretofore. It occasionally happens that, due to various causes, the abutting surfaces of the pinion and gear may engage end-to-end in such manner as to interlock and prevent rotating the pinion relative to gear in the normal direction in order to overcome gear tooth abutment. When this interlocking occurs, there was heretofore no way of relieving the interlock by continuing to press the starter pedal. The present invention however, provides that, in case of interlock (offering abnormal resistance to rotation of the pinion in the direction of rotation which manual operation of the sleeve tends to produce), continuing the endwise movement of the sleeve 52 will effect rotation of the sleeve clutch 56 in the opposite direction in order to relieve the interlock and to rotate the pinion into meshing registration with the engine gear. This is accomplished by the tang-and-oblique-slot connections 156, 157 between the sleeve 52 and its clutch 56. Normally the spring 158 will not give way sufficiently to permit the tang 156 to move into the oblique portion of the slot 157. Under abnormal conditions each tang will be moved by further operation of the pedal from the tang position 156a to the tang position 156b indicated in Fig. 14. In order that the clutch 56 will be rotated relative to the sleeve, the sleeve should be prevented from rotating. This is accomplished by providing the sleeve with the relatively abrupt shoulder 74a located between the portions 75a and 74 of the sleeve part 73 as shown particularly in Fig. 15. This shoulder 74a is engaged by the plunger 70 while the sleeve 52 is being moved endwise relative to the clutch 56 to relieve the interlocking effect. More specifically while each tang 156 is moving, relatively from the position 156a to the position 156b indicated in Fig. 14, the plunger 70 is moving from the position 70e toward the position 70f. The shoulder 74a is made so abrupt that, due to its engagement with the plunger 70, the sleeve cannot turn counterclockwise as viewed from the left in Fig. 20. Hence the sleeve 52 will not rotate but will cause the clutch 56 and pinion 26 to rotate clockwise as viewed from the left of Fig. 20 in order to relieve the abnormal condition of gear tooth abutment.

While the form of embodiment of the present invention as herein disclosed, constitutes a preferred form, it is to be understood that other forms might be adopted, all coming within the scope of the claims which follow.

What is claimed is as follows:

1. Engine starting apparatus comprising, in combination, a motor, a shaft driven thereby, a pinion driven by the shaft and movable endwise along the shaft into mesh with the

gear of an engine to be started, axially engageable clutch members, the driven member being provided by the pinion, movable endwise upon the shaft, a sleeve movable along the 5 shaft and connected with the driving clutch member, a manually operable part movable alongside the shaft, means so connecting the part and sleeve that movement of said part tends to produce endwise and rotary movement 10 of the sleeve normally in a certain direction, means yieldingly resisting rotation of the sleeve while the pinion is being moved against the engine gear and thereafter permitting the sleeve to be rotated, connections 15 between the sleeve and driving clutch providing for rotation of the latter by the former and providing a limited amount of longitudinal movement of one part relative to the other, a spring for urging the driving clutch 20 member away from the sleeve and toward the driven clutch, the connections between the clutch and sleeve providing for rotating the clutch member in a direction opposite to that normally produced by the sleeve in case the 25 sleeve is moved an abnormal amount endwise before the pinion rotates, and means for preventing rotation of the sleeve while it is being moved endwise the abnormal amount relative to the pinion.

30 2. Engine starting apparatus comprising, in combination, a motor, a shaft driven thereby, a pinion driven by the shaft and movable endwise into mesh with a gear connected with the engine to be started, a manually operable 35 member movable along the shaft for the purpose of moving the pinion into mesh with the engine gear, a sleeve movable along said shaft, connections between said sleeve and member such that the member tends to im- 40 part linear and rotary movement in a cer- tain direction to the sleeve, means for yield- 45 ingly resisting rotary movement of the sleeve until the pinion engages the gear while permitting rotation of the sleeve in case gear tooth abutment occurs, means for imparting 50 rotation in either direction from the sleeve to the pinion, and means operative in case rotation of the pinion in said certain direction is abnormally resisted and operative in response 55 to further linear movement of the sleeve, for rotating the pinion in the opposite direction.

3. Engine starting apparatus comprising, in combination, a motor, a shaft driven thereby, a pinion driven by the shaft and movable 60 endwise into mesh with a gear connected with the engine to be started, a manually oper- 65 able member movable along the shaft for the purpose of moving the pinion into mesh with the engine gear, a sleeve movable along 70 said shaft, connections between said sleeve and member such that the member tends to im- 75 part linear and rotary movement in a cer- tain direction to the sleeve, means for yield- 80 ingly resisting rotary movement of the sleeve until the pinion engages the gear while permitting rotation of the sleeve in case gear tooth abutment occurs, said means comprising a spring urged plunger movable radially relative to the sleeve and a relatively gradual, longitudinally extending shoulder provided by the 85 sleeve, a stationary guide for the plunger, clutch members for imparting rotation in either direction from the sleeve to the pinion, one member being provided by the pinion and the other connected with the sleeve, an oblique 90 spline connection between the sleeve and its clutch providing for limited linear and ro- 95 tary movement of the clutch and its sleeve, one relative to the other, a spring resisting 100 relative movement between the clutch and its sleeve, said spring yielding to permit rotation of the clutch by the sleeve in case rotation of the sleeve by the manually operable member is abnormally resisted, and means for pre- 105 venting rotation of the sleeve while moving endwise relative to the clutch, said means in- 110 cluding the beforementioned plunger and a relatively abrupt longitudinally extending shoulder engageable therewith and provided 115 by the sleeve substantially in longitudinal 120

mitting rotation of the sleeve in case gear tooth abutment occurs, said means comprising a spring urged plunger part extending transversely with respect to said sleeve and a longitudinally extending relatively gradual shoulder part engaged by said plunger, one of said parts being movable with said sleeve, clutch members for imparting rotation in either direction from the sleeve to the pinion, one of said clutch members being connected with the sleeve and the other with the pinion, means connecting the sleeve with its clutch member so as to provide for rotating the clutch in the opposite direction to normal in response to endwise movement of the sleeve relative to its clutch, a spring normally preventing rotation of the clutch relatively to the sleeve but yieldable to permit such rotation in case rotation of the sleeve by the manually operable member is abnormally resisted, and means for preventing rotation of the sleeve while moving endwise relative to the clutch, said means including the beforementioned plunger and a relatively abrupt longitudinally extending shoulder engageable therewith.

4. Engine starting apparatus comprising, in combination, a motor, a shaft driven thereby, a pinion driven by the shaft and movable endwise into mesh with a gear connected with the engine to be started, a manually operable member movable along the shaft for the purpose of moving the pinion into mesh with the engine gear, a sleeve movable along said shaft, connections between said sleeve and member such that the member tends to impart linear and rotary movement in a certain direction to the sleeve, means for yieldingly resisting rotary movement of the sleeve until the pinion engages the gear while permitting rotation of the sleeve in case gear tooth abutment occurs, said means comprising a spring urged plunger movable radially relative to the sleeve and a relatively gradual, longitudinally extending shoulder provided by the sleeve, a stationary guide for the plunger, clutch members for imparting rotation in either direction from the sleeve to the pinion, one member being provided by the pinion and the other connected with the sleeve, an oblique spline connection between the sleeve and its clutch providing for limited linear and rotary movement of the clutch and its sleeve, one relative to the other, a spring resisting relative movement between the clutch and its sleeve, said spring yielding to permit rotation of the clutch by the sleeve in case rotation of the sleeve by the manually operable member is abnormally resisted, and means for preventing rotation of the sleeve while moving endwise relative to the clutch, said means including the beforementioned plunger and a relatively abrupt longitudinally extending shoulder engageable therewith and provided by the sleeve substantially in longitudinal 130

alignment with the aforementioned less abrupt shoulder.

5. Engine starting apparatus comprising, in combination, a motor, means for connecting the motor with a gear of an engine to be started, said means comprising a pinion driven by the motor and movable endwise into mesh with the engine gear and provision whereby the pinion will be automatically disconnected from the engine gear when the engine starts, axially engageable clutch members movable longitudinally of the pinion, the driven member being provided by the pinion, a sleeve connected with the driving clutch member, a manually operable part movable alongside the sleeve, means so connecting the part and sleeve that movement of said part tends to produce endwise and rotary movement of the sleeve normally in a certain direction, means yieldingly resisting rotation of the sleeve while the pinion is being moved against the engine gear and thereafter permitting the sleeve to be rotated, connections between the sleeve and driving clutch providing for rotation of the latter by the former and providing a limited amount of longitudinal movement of one part relative to the other, a spring for urging the driving clutch member away from the sleeve and toward the driven clutch, the connections between the clutch and sleeve providing for rotating the clutch member in a direction opposite to that normally produced by the sleeve in case the sleeve is moved an abnormal amount endwise before the pinion rotates, and means for preventing rotation of the sleeve while it is being moved endwise the abnormal amount relative to the pinion.
6. Engine starting apparatus comprising, in combination, a motor, means for connecting the motor with a gear of an engine to be started, said means comprising a pinion driven by the motor and movable endwise into mesh with the engine gear and provision whereby the pinion will be automatically disconnected from the engine gear when the engine starts, a manually operable member movable longitudinally of the axis of the pinion for the purpose of moving the pinion into mesh with the engine gear, and mechanism actuated by the member and operable to move the pinion against the gear and operable normally to rotate the pinion in a certain direction into meshing registration with the engine gear in case a gear tooth abutment occurs which resists rotation of the pinion with at most a normal amount of resistance, said mechanism including provisions operable, in case rotation of the pinion in said certain direction is opposed by an abnormal amount of resistance, to rotate the pinion in the opposite direction in response to further linear movement of said member in the direction for meshing the pinion with the engine gear.

7. Engine starting apparatus comprising, in combination, a motor, a shaft provided with helical splines driven by the motor, a pinion driven by said splines and movable therealong endwise into mesh with a gear connected with the engine to be started, axially engageable clutch members, the driven member being provided by the pinion, movable endwise upon the shaft, a sleeve movable along the shaft and connected with the driving clutch member, a manually operable part movable alongside the shaft, means so connecting the part and sleeve that movement of said part tends to produce endwise and rotary movement of the sleeve normally in a certain direction, means yieldingly resisting rotation of the sleeve while the pinion is being moved against the engine gear and thereafter permitting the sleeve to be rotated, connections between the sleeve and driving clutch providing for rotation of the latter by the former and providing a limited amount of longitudinal movement of one part relative to the other, a spring for urging the driving clutch member away from the sleeve and toward the driven clutch, the connections between the clutch and sleeve providing for rotating the clutch member in a direction opposite to that normally produced by the sleeve in case the sleeve is moved an abnormal amount endwise before the pinion rotates, and means for preventing rotation of the sleeve while it is being moved endwise the abnormal amount relative to the pinion.

8. Engine starting apparatus comprising, in combination, a motor, a shaft provided with helical splines driven by the motor, a pinion driven by said splines and movable therealong endwise into mesh with a gear connected with the engine to be started, a manually operable member movable along the shaft for the purpose of moving the pinion into mesh with the engine gear, and mechanism actuated by the member and operable to move the pinion against the gear and operable normally to rotate the pinion in a certain direction into meshing registration with the engine gear in case a gear tooth abutment occurs which resists rotation of the pinion with at most a normal amount of resistance, said mechanism including provisions operable, in case rotation of the pinion in said certain direction is opposed by an abnormal amount of resistance, to rotate the pinion in the opposite direction in response to further linear movement of said member in the direction for meshing the pinion with the engine gear.

9. Engine starting apparatus comprising, in combination, a motor, a shaft provided with helical splines driven by the motor, a pinion driven by said splines and movable therealong endwise into mesh with a gear connected with the engine to be started, a manually operable member movable along

the shaft for the purpose of moving the pinion into mesh with the engine gear, a sleeve movable along said shaft, connections between said sleeve and member such that
 5 the member tends to impart linear and rotary movement in a certain direction to the sleeve, means for yieldingly resisting rotary movement of the sleeve until the pinion engages the gear while permitting rotation of the
 10 sleeve in case gear tooth abutment occurs, means for imparting rotation in either direction from the sleeve to the pinion, and means operative in case rotation of the pinion in said certain direction is abnormally resisted and
 15 operative in response to further linear movement of the sleeve, for rotating the pinion in the opposite direction.

10. Engine starting apparatus comprising, in combination, a motor, a shaft provided
 20 with helical splines driven by the motor, a pinion driven by said splines and movable therealong endwise into mesh with a gear connected with the engine to be started, a manually operable member movable along
 25 the shaft for the purpose of moving the pinion into mesh with the engine gear, a sleeve movable along said shaft, connections between said sleeve and member such that the member tends to impart linear and rotary
 30 movement in a certain direction to the sleeve, means for yieldingly resisting rotary movement of the sleeve until the pinion engages the gear while permitting rotation of the sleeve in case gear tooth abutment occurs,
 35 said means comprising a spring urged plunger part extending transversely with respect to said sleeve and a longitudinally extending relatively gradual shoulder part engaged by said plunger, one of said parts being
 40 movable with said sleeve, clutch members for imparting rotation in either direction from the sleeve to the pinion, one of said clutch members being connected with the sleeve and the other with the pinion, means
 45 connecting the sleeve with its clutch member so as to provide for rotating the clutch in the opposite direction to normal in response to endwise movement of the sleeve relative to its clutch, a spring normally preventing ro-
 50 tation of the clutch relatively to the sleeve but yieldable to permit such rotation in case rotation of the sleeve by the manually operable member is abnormally resisted, and means for preventing rotation of the sleeve
 55 while moving endwise relative to the clutch, said means including the beforementioned plunger and a relatively abrupt longitudinally extending shoulder engageable there-
 60 with.
 65 11. Engine starting apparatus comprising, in combination, a motor, a shaft provided with helical splines driven by the motor, a pinion driven by said splines and movable there-
 70 along endwise into mesh with a gear connect-
 75 ed with the engine to be started, a manually
 80 operable member movable along the shaft
 85 for the purpose of moving the pinion into
 90 mesh with the engine gear, a sleeve movable
 95 along said shaft, connections between said
 100 sleeve and member such that the member
 105 tends to impart linear and rotary movement
 110 in a certain direction to the sleeve, means for
 115 yieldingly resisting rotary movement of the
 120 sleeve until the pinion engages the gear while
 125 permitting rotation of the sleeve in case
 130 gear tooth abutment occurs, said means
 135 comprising a spring urged plunger movable
 140 radially relative to the sleeve and a relatively
 145 gradual, longitudinally extending shoulder
 150 provided by the sleeve, a stationary guide for
 155 the plunger, clutch members for imparting ro-
 160 tation in either direction from the sleeve to the
 165 pinion, one member being provided by the
 170 pinion and the other connected with the
 175 sleeve, an oblique spline connection between
 180 the sleeve and its clutch providing for limited
 185 linear and rotary movement of the clutch and its
 190 sleeve, one relative to the other, a spring
 195 resisting relative movement between the
 200 clutch and its sleeve, said spring yielding
 205 to permit rotation of the clutch by the sleeve
 210 in case rotation of the sleeve by the manually
 215 operable member is abnormally resisted, and
 220 means for preventing rotation of the sleeve
 225 while moving endwise relative to the clutch,
 230 said means including the beforementioned
 235 plunger and a relatively abrupt longitudinally
 240 extending shoulder engageable there-
 245 with and provided by the sleeve substantial-
 250 ly in longitudinal alignment with the afore-
 255 mentioned less abrupt shoulder.

12. Engine starting apparatus comprising, in combination, a motor, a shaft provided with helical splines driven by the motor, a pinion driven by said splines and movable therealong endwise into mesh with a gear connected with the engine to be started, axially engageable clutch members, the driven member being provided by the pinion, movable endwise upon the shaft, a sleeve
 105 movable along the shaft and connected with the driving clutch member, a manually operable part movable alongside the shaft, means so connecting the part and sleeve that movement of said part tends to produce endwise and rotary movement of the sleeve normally in a certain direction, means yieldingly resisting rotation of the sleeve while the pinion is being moved against the engine gear and thereafter permitting the sleeve to be rotated, connections between the sleeve and driving clutch providing for rotation of the latter by the former and providing a limited amount of longitudinal movement of one part relative to the other, a spring for urging the driving clutch member away from the sleeve and toward the driven clutch, the connections between the clutch and sleeve providing for rotating the clutch member in a direction opposite to that normally pro- 115

duced by the sleeve in case the sleeve is moved an abnormal amount endwise before the pinion rotates, means for preventing rotation of the sleeve while it is being moved endwise 5 the abnormal amount relative to the pinion, and provisions whereby the sleeve will automatically be retracted from the engine gear before the engine starts, regardless of whether the manually operable part has been released.

10 13. Engine starting apparatus comprising, in combination, a motor, a shaft provided with helical splines driven by the motor, a pinion driven by said splines and movable therealong endwise into mesh with a gear connected with the engine to be started, a manually operable member movable along the shaft for the purpose of moving the pinion into mesh with the engine gear, mechanism 15 actuated by the member and operable to move the pinion against the gear and operable normally to rotate the pinion in a certain direction into meshing registration with the engine gear in case a gear tooth abutment occurs which resists rotation of the pinion with at most a normal amount of resistance, said mechanism including provisions operable, in case rotation of the pinion in said certain direction is opposed by an 20 abnormal amount of resistance, to rotate the pinion in the opposite direction in response to further linear movement of said member in the direction for meshing the pinion with the engine gear, and provisions whereby said 25 pinion moving mechanism will automatically be retracted from the pinion before the engine starts, regardless of whether the manually operable part has been released.

14. Engine starting apparatus comprising, in combination, a motor, a shaft provided with helical splines driven by the motor, a pinion driven by said splines and movable therealong endwise into mesh with a gear connected with the engine to be started, a manually operable member movable along the shaft for the purpose of moving the pinion into mesh with the engine gear, a sleeve movable along said shaft, connections between said sleeve and member such that the member tends to impart linear and rotary movement in a certain direction to the sleeve, means for yieldingly resisting rotary movement of the sleeve until the pinion engages the gear while permitting rotation of the sleeve in case gear tooth abutment occurs, means for imparting rotation in either direction from the sleeve to the pinion, means operative in case rotation of the pinion in said certain direction is abnormally resisted and operative in response to further linear movement of the sleeve, for rotating the pinion in the opposite direction, and provisions whereby the sleeve will be automatically retracted from the pinion before the

engine starts regardless of whether the manually operable member has been released.

15. Engine starting apparatus comprising, in combination, a motor, a shaft provided with helical splines driven by the motor, a pinion driven by said splines and movable therealong endwise into mesh with a gear connected with the engine to be started, a manually operable member movable along the shaft for the purpose of moving the pinion into mesh with the engine gear, a sleeve movable along said shaft, connections between said sleeve and member such that the member tends to impart linear and rotary movement in a certain direction to the sleeve, means for yieldingly resisting rotary movement of the sleeve until the pinion engages the gear while permitting rotation of the sleeve in case gear tooth abutment occurs, said means

70 comprises a spring urged plunger part extending transversely with respect to said sleeve and a longitudinally extending relatively gradual shoulder part engaged by said plunger, one of said parts being movable with said sleeve, clutch members for imparting rotation in either direction from the sleeve to the pinion, one of said clutch members being connected with the sleeve and the other with the pinion, means connecting the sleeve with its clutch member so as to provide for rotating the clutch in the opposite direction to normal in response to endwise movement of the sleeve relative to its clutch, a spring normally preventing rotation of the clutch relatively to the sleeve but yieldable to permit such rotation in case rotation of the sleeve by the manually operable member is abnormally resisted, means for preventing rotation of the sleeve while moving endwise relative to the clutch, said means including the beforementioned plunger and a relatively abrupt longitudinally extending shoulder engageable therewith, and provisions whereby the sleeve will be automatically retracted from the pinion before the engine starts, regardless of whether the manually operable member has been released.

75 100 105 110 115 120 125 130

16. Engine starting apparatus comprising, in combination, a motor, a shaft provided with helical splines driven by the motor, a pinion driven by said splines and movable therealong endwise into mesh with a gear connected with the engine to be started, a manually operable member movable along the shaft for the purpose of moving the pinion into mesh with the engine gear, a sleeve movable along said shaft, connections between said sleeve and member such that the member tends to impart linear and rotary movement in a certain direction to the sleeve, means for yieldingly resisting rotary movement of the sleeve until the pinion engages the gear while permitting rotation of the sleeve in case gear tooth abutment occurs, said means comprising a spring urged plunger

- movable radially relative to the sleeve and a relatively gradual, longitudinally extending shoulder provided by the sleeve, a stationary guide for the plunger, clutch members for imparting rotation in either direction from the sleeve to the pinion, one member being provided by the pinion and the other connected with the sleeve, an oblique spline connection between the sleeve and its clutch providing for limited linear and rotary movement of the clutch and its sleeve, one relative to the other, a spring resisting relative movement between the clutch and its sleeve, said spring yielding to permit rotation of the clutch by the sleeve in case rotation of the sleeve by the manually operable member is abnormally resisted, means for preventing rotation of the sleeve while moving endwise relative to the clutch, said means including the aforementioned plunger and a relatively abrupt longitudinally extending shoulder engageable therewith and provided by the sleeve substantially in longitudinal alignment with the aforementioned less abrupt shoulder, and provisions whereby the sleeve will be automatically retracted from the pinion before the engine starts, regardless of whether the manually operable member has been released.
17. Engine starting apparatus comprising, in combination, a motor, means for connecting the motor with an engine to be started and including a pinion movable endwise along the shaft driven by the motor and into mesh with a gear connected with the engine, and including provisions whereby the pinion will be automatically disconnected from the engine gear when the engine starts, a pinion pushing and turning member movable along said shaft, and manually operable means for axially moving and rotating said member and comprising a sleeve movable along said shaft and having an oblique slot receiving an actuating pin, means for connecting the sleeve and the pinion pushing and turning member, said means providing for relative longitudinal movement between the sleeve and member and for relative rotary movement accompanying said relative longitudinal movement, said member tending to rotate relative to the sleeve in a direction opposite to that in which the sleeve tends to rotate when actuated by the pin, yielding means for holding the sleeve and pinion pushing and rotating member in extended relation, and means for resisting rotation of the sleeve.
18. Engine starting apparatus comprising, in combination, a motor, means for connecting the motor with an engine to be started and including a pinion movable endwise along the shaft driven by the motor and into mesh with a gear connected with the engine, and including provisions whereby the pinion will be automatically disconnected from the engine gear when the engine starts, axially

engageable clutch members movable along the shaft, the driven member being provided by the pinion, manually operable means for axially moving and rotating said driving clutch member and comprising a sleeve movable along said shaft and having an oblique slot receiving an actuating pin, means for connecting the sleeve and driving clutch member and providing for relative longitudinal movement between the sleeve and driving clutch member and for relative rotary movement accompanying said relative longitudinal movement, said driving clutch member tending to rotate relative to said sleeve in a direction opposite to that in which the sleeve tends to rotate when actuated by the pin, yielding means for holding the sleeve and driving clutch member in extended relation and means for resisting rotation of the sleeve.

19. Engine starting apparatus comprising, in combination, a motor, means for connecting the motor with an engine to be started and including a pinion movable endwise along the shaft driven by the motor and into mesh with a gear connected with the engine, and including provisions whereby the pinion will be automatically disconnected from the engine gear when the engine starts, axially engageable clutch members movable along the shaft, the driven member being provided by the pinion, manually operable means for axially moving and rotating said driving clutch member and comprising a sleeve movable along said shaft and having an oblique slot receiving an actuating pin, an oblique slot provided by said sleeve for receiving a lug connected with the driving clutch member, said last mentioned oblique slot extending in a direction transverse to the first mentioned oblique slot of the sleeve, yielding means for holding the sleeve and driving clutch member in extended relation and means for resisting rotation of the sleeve.

20. Engine starting apparatus comprising, in combination, a motor, a helically splined shaft driven by the motor, a pinion drivingly connected with said splines and movable therewith into mesh with a gear of an engine to be started, said pinion being provided with a clutch member, a driving clutch member axially engageable with the pinion clutch member and movable along said shaft, manually operable means for axially moving and rotating said driving clutch member and comprising a sleeve movable along said shaft and having an oblique slot receiving an actuating pin, an oblique slot provided by said sleeve for receiving a lug connected with the driving clutch member, said last mentioned oblique slot extending in a direction transverse to the first mentioned oblique slot of the sleeve, yielding means for holding the sleeve and driving clutch member in extended relation and means for resisting rotation of the sleeve.

21. Engine starting apparatus comprising, in combination, a motor, a helically splined shaft driven by the motor, a pinion drivingly connected with said splines and movable therealong into mesh with a gear of an engine to be started, said pinion being provided with a clutch member, a driving clutch member axially engageable with the pinion clutch member and movable along said shaft, manually operable means for axially moving and rotating said driving clutch member and comprising a sleeve movable along said shaft, and having an oblique slot receiving an actuating pin; an oblique slot provided by said sleeve for receiving a lug connected with the driving clutch member, said last mentioned oblique slot extending in a direction transverse to the first mentioned oblique slot of the sleeve, a spring encircling the shaft for holding the sleeve and driving clutch in extended relation, means for yieldingly resisting rotary movement of the sleeve until the pinion engages the gear while permitting rotation of the sleeve in case gear tooth abutment occurs, said means comprising a spring urged plunger part extending transversely with respect to said sleeve and a longitudinally extending relatively gradual shoulder part engaged by said plunger, one of said parts being movable with said sleeve, and means for preventing rotation of the sleeve while moving endwise relative to the clutch, said means including the beforementioned plunger and a relatively abrupt longitudinally extending shoulder engageable therewith. 70
